(57) **CLAIM**

The ornamental design for an optical disc driving device, as shown.

DESCRIPTION

FIG. 1 is a perspective view of the front, top and right sides of an optical disc driving device showing our new design; FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is a perspective view of the front, bottom and left sides thereof.
